UNITED STATES PATENT OFFICE

121,201

DESIGN FOR A PROPELLER

Max Fischer, Great Neck, N. Y.

Application September 22, 1939, Serial No. 87,353

Term of patent 3½ years

To all whom it may concern:

Be it known that I, Max Fischer, a citizen of the United States of America and residing at Great Neck, Long Island, in the State of New York, have invented a new, original, and ornamental Design for a Propeller, of which the following is a specification, reference being had to the accompanying drawing, forming part thereof, wherein

Figure 1 is a plan view of a propeller showing my new design.

Figure 2 is a side elevation thereof.

I claim:

The ornamental design for a propeller, substantially as shown.

MAX FISCHER.
